(57) CLAIM

The ornamental design for cosmetic brushes having a fan-like shape, as shown and described.

DESCRIPTION

FIG. 1 is a perspective view of a cosmetic brush having a fan-like shape according to an exemplary embodiment of the present design;

FIG. 2 is a right side elevational view of the cosmetic brush having a fan-like shape shown in FIG. 1;

FIG. 3 is a left side elevational view of the cosmetic brush having a fan-like shape shown in FIG. 1;

FIG. 4 is a rear elevational view of the cosmetic brush having a fan-like shape shown in FIG. 1;

FIG. 5 is a front elevational view of the cosmetic brush having a fan-like shape shown in FIG. 1;

FIG. 6 is a top plan view of the cosmetic brush having a fan-like shape shown in FIG. 1; and,

FIG. 7 is a bottom plan view of the cosmetic brush having a fan-like shape shown in FIG. 1.

Applicant respectfully submits that the broken or dashed line format lines shown herein are for illustrative purposes only and form no part of the claimed design.

1 Claim, 3 Drawing Sheets
